UNITED STATES PATENT OFFICE.

SAMUEL P. RUFF, JR., OF CHESTER, PENNSYLVANIA.

METHOD OF TREATING YARNS FOR KNITTING.

No Drawing.

Application filed April 3, 1923. Serial No. 629,575.

My invention relates to methods of treating yarns for use in knitting.

The fibrous surfaces of the yarns as they come from the original package involve too much friction in the subsequent operations for successful mechanical knitting and it has been found practically essential to smooth or soften these surfaces before the yarns enter the knitting machines.

10 The standard original package contains 378 strands of yarn in some kind of coil and is known in shop parlance as a "ball". If the yarn from a ball passes through a mercerizing process it is again disposed in a coil but, in shop parlance is called a "bale", though the shape of the coil may be identical with that of the original "ball", and, like the "ball" it contains 378 strands of yarn. In passing to the knitting operation 20 the strands pass through a reed, then over a yarn roller, then to a guiding frame which guides the individual strands to the respective cones, bobbins, spools or other winding agent upon which they are wound and 25 from which they pass to the knitting operation. The term winding unit as hereinafter used is intended to denote any element upon which individual yarns are wound.

20 The usual practice is to apply the smoothing agent, which is usually a bar of wax, to the individual yarns after they leave the guiding frame and either just before they reach the winding unit or after they leave that unit and before they reach the knitting 30 operation.

The perfection of the knitting depends in large degree upon the perfection with which the smoothing and winding operations are effected and the consequent uniformity of tension upon the yarns.

35 The old method requires 378 independent waxing units and uniformity of waxing or tension is impossible.

40 The strands coming from the ball or bale 45 pass from the reed to the yarn roller in a single ply sheet composed of 378 parallel and closely adjacent strands, hereinafter called the warp. By applying the smoothing agent to the warp before it reaches the

guiding frame which directs the individual strands to the respective winding units, a single smoothing agent does the work which previously required 378 independent units and practical uniformity of both waxing and tension may be obtained. I prefer to apply the smoothing agent to the warp after it leaves the reed and before it reaches the 50 55 yarn roller, but the essential factor is that it be applied before the strands are caused to diverge from each other to be guided to the respective winding units.

The waxing or smoothing may be effected by causing the warp to travel across a bar of wax, preferably movable to cause a rolling movement of the yarns, or by causing the 60 65 yarns to travel across a surface, preferably rotatable, which is moistened with a waxy fluid or a vegetable oil.

By this method the yarns are smoothed and softened and their potential friction reduced at the earliest possible stage, the smoothing and softening is much more uniform, the winding operations are much more perfectly effected, the tension upon the 70 75 yarn in both winding and knitting operations is much more uniform, and the proportion of seconds is reduced to a negligible quantity.

Having thus described my invention, what I claim as new and desire to secure by Letters Patent is:—

1. The method of treating yarns for knitting purposes consisting in passing multiple strands of yarn over a smoothing agent, having a movement which will impart a rolling action to the strands of yarn, substantially as described.

2. The herein described method of treating yarns for knitting operations consisting in applying a smoothing agent to the yarns as they come from the original package before 90 the strands are diverted from each other to pass to the winding units, said smoothing agent, having a movement which will impart a rolling action to the strands of yarn.

In testimony whereof I have signed my 95 name to this specification.

SAMUEL P. RUFF JR.
